US00D745045S

(12) **United States Design Patent**
Heeter et al.

(10) **Patent No.:** US D745,045 S
(45) **Date of Patent:** ** Dec. 8, 2015

(54) **DISPLAY SCREEN WITH GRAPHICAL USER INTERFACE**

(71) Applicant: **Microsoft Corporation**, Redmond, WA (US)

(72) Inventors: **Ross David Heeter**, Seattle, WA (US); **Jason Robert Tuck**, Kirkland, WA (US); **Silas Varga**, Seattle, WA (US); **Alex Anthony Tursi**, Seattle, WA (US)

(73) Assignee: **Microsoft Corporation**, Redmond, WA (US)

(**) Term: **14 Years**

(21) Appl. No.: **29/470,840**

(22) Filed: **Oct. 25, 2013**

(51) LOC (10) Cl. **14-04**

(52) U.S. Cl. **USPC** **D14/489**

(58) **Field of Classification Search**

USPC **D14/485-495**
CPC G06F 3/048; G06F 3/04817; G06F 3/0482
See application file for complete search history.

Primary Examiner — Kevin Rudzinski

(74) Attorney, Agent, or Firm — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showing of the text, the remainder of the user interface, and the remainder of the display screen is for environmental purposes only and forms no part of the claimed design.

1 Claim, 1 Drawing Sheet
